UNITED STATES PATENT OFFICE.

GEORGE SOMERVILLE, OF DENVER, COLORADO.

DESIGN FOR A FOOT SCRAPER FOR AUTOMOBILES.

Application filed March 7, 1923. Serial No. 5,396. Term of patent 3½ years.

To all whom it may concern:

Be it known that I, GEORGE SOMERVILLE, a citizen of the United States, residing at Denver, in the county of Denver and State of Colorado, have invented a new, original, and ornamental Design for a Foot Scraper for Automobiles, of which the following is a specification, reference being had to the accompanying drawing, forming part thereof.

Figure 1 represents a face view of a foot

scraper for automobiles showing my new design; and

Figure 2, a section taken on the line 2—2, Figure 1.

I claim:

The ornamental design for a foot scraper for automobiles as shown.

In testimony whereof I have affixed my signature.

GEORGE SOMERVILLE.
